TROUBLE DETECTOR AND ELECTRICAL CONTACTOR THROUGH INSULATED CONDUCTORS

Carlos Mantilla, New York, N. Y.

Application March 16, 1939, Serial No. 262,167

1 Claim. (Cl. 175—183)

This invention relates to new and useful improvements in a trouble detecting and current taking device, for electrical circuits by means of penetrating the insulation and contacting the leads.

With specific reference to the electrical circuit trouble detector this invention contemplates the construction of a detector which is characterized by a pair of pivotally connected jaws, one of which is provided with a lamp socket into which a lamp may be screwed, and the other of which is adapted to be connected with an electric circuit plug so that when the jaws are closed the lamp will light signifying that the circuit is all right. If the lamp does not light, it will mean that there is no current in the circuit.

Still further the invention proposes the provision of a handle portion on each jaw element on the opposite side to their pivot by which they may be manually moved.

Another one of the objects of this invention resides in so arranging the electric circuit plugs that they may be engaged into grooves formed in the jaw element and may support the detector device in this position.

Still further the invention proposes a modified form embodying the apparatus in a shape to be used to contact each lead separately and form a different circuit.

Still further the invention proposes to arrange pins or other pointed contact elements upon the jaw provided with the lamp socket, which contact elements are electrically connected with the socket and adapted to close the circuit from the plugs to the socket when the jaws are closed.

Still further the invention proposes the construction of a trouble detector for electric circuits, in the form of a pair of pliers constructed from Bakelite or similar material and which is provided with cutaway portions upon the adjacent sides of the jaws through which electric wires are adapted to pass.

Still further it is proposed to provide a plurality of metallic pins fixedly mounted in one of the cutaway portions and extendable into the other of the cutaway portions for short circuiting the wires passing between the jaws to determine whether or not current is passing therethrough.

Still further the invention proposes the construction of a trouble detector for electric circuits characterized by a body member constructed of separate sections fixedly held together in face contact, and the provision of grooves extending along one of the adjacent faces for

forming passages through which electric leads may be passed.

Still further it is proposed to provide the other of the sections with recesses extended inwards from its outer face and superimposed above said grooves.

Still further it is proposed to extend contact members through the section having the recesses in a manner so that one end of the contact members will extend into said grooves for contacting the electric leads passing therethrough while the other ends of the contact members will be exposed within said recesses to permit the said latter mentioned ends to be contacted for determining whether or not said leads are carrying electricity.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

25 Fig. 1 is a side elevational view of a trouble detector for electric circuits constructed according to this invention.

Fig. 2 is a sectional view taken on the line 2—2 of Fig. 1.

Fig. 3 is an elevational view of a contact element connected through a fuse which may be substituted for the contact elements shown in Fig. 2, Fig. 4, and Fig. 8.

Fig. 4 is a perspective view of a trouble detector for electric circuits constructed according to a modification of the invention.

Fig. 5 is an enlarged sectional view on the line 5—5 of Fig. 4.

Fig. 6 is a sectional view on the line 6—6 of Fig. 4.

Fig. 7 is a sectional view on the line 7—7 of Fig. 4.

Fig. 8 is a perspective view of a modified form of this invention embodying the apparatus in a shape as to be used to contact the leads separately to form a different circuit.

Fig. 9 is a sectional view on the line 9—9 of Fig. 8.

Fig. 10 is a sectional view on the line 10—10 of Fig. 8.

The trouble detector for electric circuits, according to this invention, comprises a pair of pivotally connected jaws 10 and 11, pivotally connected by a pintle 12. Each of these jaw elements has a handle portion on the side oppo-

site to the pivot 12. The handle portion of the jaw 10 is indicated by numeral 10^a, while that of the jaw 11 by 11^a. A spring 13 is mounted between the handle portions and acts to normally urge the handle portions apart and consequently the jaws apart.

An insulation member 14 is mounted on the jaw 10, and is superimposed over an insulation member 15 mounted on the jaw 11. The insulation member 15 is formed with grooves 16 for receiving electric circuit plugs 17. These plugs may be secured upon a support 18 and have a dual function. First, they are capable of supplying electricity from a circuit not illustrated on the drawing; second, they are capable of supporting the trouble detector. The detector may be removed by merely gripping it by the handle portions and pulling it off the plugs.

A lamp socket 19, wires 20 and 21, and contact fingers 22 and 23 are mounted upon the other of said insulation members, namely, the member 14. The socket 19 is adapted to receive an electric light bulb 24 which is to be used for detecting trouble. The contact fingers are in the form of studs which are screwed into the insulation member 14 at positions directly above the grooves 16. The wire 21 connects the end contact 19^a of the socket 19 with the contact finger 23. The wire 20 connects the shell contact 19^b of the socket 19 with the finger 22. Each of the contact fingers have several pins 22^a and 23^a, respectively, which are removably held in position by set screws 25. These pins may be released when desired. They are located immediately above the grooves 16 and are adapted to engage the plugs 17 for closing the electric circuit.

The grooves 16 are of dove-tailed form as clearly shown in Fig. 2, and are cooperative with the plugs 17 which are of a complementary shape.

Trouble in the electric circuit may be detected by squeezing together the handle portions 10^a and 11^a. This causes the jaws to close and the contact pins 22^a and 23^a to connect with the plugs 17. If there is current in the plugs 17, the lamp 24 will light, signifying that the circuit is all right. If, however, there is no current in the plugs 17, the lamp will not light, indicating trouble in the circuit.

In Fig. 3 a modified form of contact finger 26 is illustrated. This contact finger has a fuse 26^a from which a plurality of pins 26^b project. The head, portion 26^a may be glued into grooves made in the insulation members 14 and 31. The electric lead to place the contact fingers in the electric circuit may be soldered to the inner face of the head 26^a.

According to the modification of the invention shown in Figs. 4-7 inclusive the trouble detector for electric circuits includes a pair of jaws 30 and 31 pivotally connected together by means of a pin 32. The jaw 30 is formed with a handle portion 30^a which extends to the other side of the pivot 32 and jaw 31 is formed with a similar handle 31^a which extends to the other side of the pivot 32. The jaws 30 and 31 are urged into a normal closed position by means of a leaf spring 33 which operates between the adjacent faces of the handle portions 30^a and 31^a. Thus when the handle portions 30^a and 31^a are urged together, the jaws 30 and 31 will be moved to the open position. The jaw element 30 is formed with an outwardly extending lug 30^b which is adapted to extend along a similar outwardly extending lug 31^b formed on the jaw element 31.

The pivot 32 extends through the overlapping lugs 30^b and 31^b for pivotally connecting the jaws 30 and 31.

Each of the jaws 30 and 31 is formed with a cutaway portion. The jaw 30 is formed with a cutaway portion 34 and the jaw 31 is formed with a cutaway portion 35. These cutaway portions are formed in the adjacent faces of the jaws 30 and 31 and are adapted to be aligned with each other in the closed position of the jaws for forming a passage between the jaws through which wires are adapted to be passed.

A plurality of metallic pins 36 are mounted in the cutaway portion of one of the jaws and are adapted to extend into the cutaway portion of the other of the jaws for short circuiting the wires passing between the jaws. As shown in the drawing the metallic pins 36 are mounted within the cutaway portion in the jaw 30 and extend into the cutaway portion in the jaw 31. This is merely for the purpose of illustration and the metallic pins 36 may be mounted within the cutaway portion of the jaw 31 and extend into the cutaway portion of the jaw 30. In place of the pins 36 a single blade similar to a safety razor blade may be used.

The drawing illustrates that the jaws 30 and 31, as well as their respective handle portions, are constructed from insulation material such as Bakelite or other similar material but the jaws may be constructed from a metallic substance and have insulation material set into the adjacent edges thereof and the cutaway portions may be formed in the insulation material.

The operation of the device is as follows:

For determining whether or not a set of electric leads are carrying a current the handle portions 30^a and 31^a are adapted to be squeezed together for separating the jaws 30 and 31. This permits the set of electric leads to be engaged into the cutaway portions 34 and 35. When the leads are aligned with these cutaway portions the handles 30^a and 31^a may be released to permit the spring 33 to return them to their normal position which will cause the metallic pins 36 to pierce the insulation on the electric leads to contact the wires to short circuit them.

According to the modification of the invention shown in Figs. 8-10 inclusive the trouble detector for electric circuits includes a body member 40 constructed of separate sections 40^a and 40^b. These sections are constructed from insulation material and are fixedly held together in face contact by means of a bolt 41 which passes axially therethrough.

One of the sections, namely, the section 40^b is formed with a pair of parallel grooves 42 which extend across one of the adjacent faces for forming passageways through which the electric leads are adapted to be passed. These grooves 42 are so positioned with relation to the inner face of the sections 40^b, which is adapted to contact the adjacent face of the section 40^a, that they extend inwards therefrom. The inner face of the section 40^a extends across the open top of the grooves 42 and completes the passageway through which electric leads are adapted to pass.

The other of the sections, namely the sections 40^a, is formed with recesses 43 in its outer face. These recesses are formed by cutting away a portion of the outer face of the section 40^a. Each of the recesses 43 is superimposed above one of the pair of grooves 42. Contact members 44 are mounted through the section having the recesses 43 and each of the contact members has

one of its ends extending into one of the pair of grooves 42 and the other of its ends exposed within the recesses 43 so that the portions exposed within the recesses may be contacted for short circuiting the electric leads passing through the grooves 42 to determine whether or not the electric leads are carrying a current.

The ends of the contact members which extend into the grooves 42 are formed with enlarged heads 44^a and a plurality of projecting pins 45 are attached to the free face of the heads 44^a for contacting and tightly bearing against the leads passing through the grooves 42 for making a positive contact therewith. The other ends 44^b of the contact members 44 are bent upon themselves and the adjacent faces of these portions are slightly spaced from each other for giving the bent over end a slight resiliency so as to tightly engage against the members inserted into the recesses 43 for making a positive contact therewith to short circuit the wires.

The operation of this form of the device is as follows:

The body member 40 is fixedly attached upon the electric leads of an electric circuit by removing the bolt 41 and baring a portion of the electric leads at points where they are adapted to pass through the grooves 42 for permitting the pins 45 of the contact members 44 to engage the said wires. This body member 40 remains in position upon the electric leads and at such time when it becomes necessary to detect whether or not there is trouble in a certain electric circuit

the same may be accomplished by engaging a short circuiting member of any desired construction into the recesses 43 so as to engage the ends 44^b of the contact members and short circuit the leads passing through the grooves 42.

While I have illustrated and described the preferred embodiments of my invention, it is to be understood that I do not limit myself to the precise constructions herein disclosed and the right is reserved to all changes and modifications coming within the scope of the invention as defined in the appended claim.

I claim:

In a device of the class described, a pair of pivotally connected jaws each having a cut-away portion of U-shape on their opposing faces, said cut-away portions being aligned with each other forming an opening which, in the closed position of said jaws, extends through the jaws at right angles to the length thereof, said opening being of a size to permit an electric wire to pass therethrough when said jaws are in closed position, one of said jaws being formed with an auxiliary opening extended inwards from the base of its U-shaped cut-away portion, and a plurality of pins having their dull ends embedded in the material of the other jaw at the base of its respective cut-away portion, said pins having their pointed ends extended across said first-mentioned opening and freely extended into said auxiliary opening when said jaws are in closed position.

CARLOS MANTILLA.
